UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,107,307.

Specification of Letters Patent.

Patented Aug. 18, 1914.

Original application filed October 13, 1911, Serial No. 654,500. Divided and this application filed December 3, 1912. Serial No. 734,679.

To all whom it may concern:

Be it known that I, HARRY J. HICK, a citizen of the United States, residing at Alliance, in the county of Stark and State 5 of Ohio, have invented certain new and useful Improvements in and Relating to Filing Appliances, of which the following is a specification.

This invention relates to appliances or 10 devices that are adapted to receive and hold papers, documents, paper slips, and similar articles and permitting them to be classified under suitable headings, whereby they may be inserted, removed or inspected rapidly and in a simple manner.

This application is a division of my application filed October 13, 1911, Serial Number 654,500.

For the purpose of illustration, I have, in 20 the accompanying drawings, shown and herein described one form of filing appliance embodying my invention.

Figure 1 is a side elevation of an appliance embodying my invention, parts of the 25 casing being broken away. Fig. 2 is a fragmentary sectional view through the lower portion of the holders. Fig. 3 is a fragmentary bottom plan view of the holders. Fig. 4 is a fragmentary perspective view of 30 two holders and the pivotal connections between them. Fig. 5 is a perspective view of one of the pivotal connections. Fig. 6 is a perspective view of the parts shown in Fig. 5 detached. Fig. 7 is a fragmentary 35 view with parts broken away.

In the drawings, 1 indicates a suitable casing having a platform or support 1^a, a back 1^b, and a forwardly extending frame 1^c which may serve as a writing desk. The 40 casing may also include side members, between which may be provided one or more drawers or trays 1^e.

2 indicates a series of holders for holding or supporting papers, or paper slips, and 45 comprising a front or forward end holder 2^a, a back or rear end holder 2^b, and a plurality of intermediate holders 2^c. All the holders are preferably of uniform size, and may be normally arranged back to back in 50 vertical position.

Each holder comprises a back 2^d, which is preferably formed from sheet metal, a hinge bar 2^e, side members 2^f, spacing devices 2^g,

and paper clips 2^h. The hinge bars 2^e extend from end to end along the lower end of 55 the holders. Each bar is preferably formed by extending the metal of the adjacent back and bending it into a hollow rectangular bar. The free edge of the metal may be arranged flat against and secured to the adjacent back by rivets 2ⁱ. The side members 2^f being arranged along the opposite sides of the backs, protect the edges thereof and also maintain the backs substantially 60 parallel with each other. The spacing devices on opposite faces of each back are preferably aligned with each other and secured to the adjacent back by a single rivet 2^j. At 2^h each clip is provided with a plate 70 which forms a back or support for a heading or eye signal. Only one clip or slip engaging device 2^h is shown in the drawings, but it will be understood that I provide a series of such devices on both faces of each back 2^d, except the backs of the front 75 and rear holders, which are only provided with clips on their inner faces. At 2ⁱ, the front and rear holders are provided with external plates or walls, formed from sheet metal, which give said holders a neat 80 and finished appearance.

3 indicates pivotal connections between the holders 2 connecting said holders together and permitting each to move or swing relative to the adjoining holder. By this 85 construction the holders may be operated one by one or in groups from the vertical to the horizontal position, and vice versa, for the purpose of exposing either face of any desired holder. The connections 3 comprise a series of devices 3^a, at least one of 90 which is carried by each holder, a plate 3^b interposed between each device 3^a and the adjacent hinge bar 2^e and provided with pivot bearing members 3^c depending from 95 their opposite ends, which members are preferably integrally connected with the plates 3^b, and pintles or pivot pins 3^d each of which connects adjacent pivotal bearing plates together. As clearly shown in the 100 drawings each device 3^a is formed from a piece or section of sheet metal and pressed or bent on longitudinal lines to encircle and snugly fit the walls of the hinge bar with the plate 3^b interposed between it and the 105 hinge bar 2^e. The opposite longitudinal

ends of the section of metal forming a device 3^a are preferably bent and arranged to lie flat against the opposite faces of the adjacent back 2^a. These ends may be secured 5 to the back by rivets 2^c. The shape of the hinge bar in cross section prevents any relative movement between it and the supporting device 3^a in a direction circumferentially of the said bar.

10 The plates 3^b are of a width to fit snugly between the side walls of the supporting device 3^a and are also of such length that the depending bearing members engage with the opposite end edges of the supporting device 3^a. As the supporting device 3^a is arranged to snugly fit the side walls of the hinge bar 2^a and the bottom face of the plate 3^b, the latter will be rigidly secured in position and maintained against movements 15 in longitudinal or lateral directions. The bearing members 3^b will therefore be supported at right angles to the hinge bars 2^a. The plates 3^b and bearing members 3^b may be stamped or otherwise formed from a single piece of sheet metal.

20 At 3^d, each bearing member 3^b is formed with openings near its opposite ends to receive the pintles 3^e, the openings in one member alining with the openings in the member 25 at the opposite side of the adjacent supporting device 3^a. As will be understood, the openings 3^d in the members 3^b of a device 3^a carried by one holder register with the openings 3^d of the member carried by the device 3^a of the adjoining holder or holders to receive the pintles 3^e. Since each pintle 3^e is of a length to extend through the alined openings in the bearing members of the pivot connections between adjoining holders, 30 a long bearing is provided. The opposite ends of each pintle 3^e are preferably up-set on the opposite outer bearing members of each two adjoining pivotal devices 3^a on the same bar. They are of a length so that after the 35 up-setting operation, they maintain the inner bearing members of said devices in close engagement with the interposed members of the device 3^a on the adjacent bar and thus prevent endwise movement of one holder relative to the adjoining holder or holders. 40 As the bearing members depend downwardly vertically from the hinge bar 2^a, it will be seen that one forms a bearing for the other, as the adjacent holder is operated. Preferably I provide each alternate hinge bar 2^a with one pivot connection 3^a and each of the 45 remaining hinge bars 2^a with two pivot connections 3^a which are arranged on opposite sides of the connections 3^a on the alternate hinge bars. This arrangement not only provides a very long and durable bearing for the 50 hinge bars, but serves to keep them in alinement since each pintle has support on one hinge bar upon opposite sides of its bearing 55 connection with the adjoining hinge bar.

4 indicates a bearing mounted on the support 1^a and arranged to removably receive a pivot 3^c carried by bearing plates 3^b at the forward edge of the front holder 2^a. This support being at the forward end of the 70 series of holders 2, maintains them in upright position with the rear holder against the back 1^b, or a yielding device 5, which may be provided thereon. This support also forms the pivot for the front holder and 75 those holders which may be operated therewith as a group at any time. Since the holders are connected together at their hinged ends, it will be understood that the horizontal position serves to move the hinged 80 ends of the remaining holders forwardly and upwardly; the operation of the holders back to the vertical position moves the hinged ends downwardly and backwardly.

85 6 indicates a device preferably carried by the back 1^b for guiding the rear holder in its up and down movements.

90 The operative position of the guide device 6 is shown in dotted lines in Fig. 1. In the form of the invention herein illustrated and described, the rearward leaves are moved forwardly and upwardly when any of the forward leaves are operated from the vertical to the horizontal position; when the operated leaves are returned to the vertical position, the rearward leaves move rearwardly and downwardly. The guide device 6 is arranged to be engaged by the upper or free edge of the rearmost leaf and as said rearmost leaf moves upwardly or downwardly 95 it is guided in such movements by the device 6. The guide device 6 may be provided with a latch 6^a at or near its free end. This latch is so arranged that when all of the leaves have been operated, except the rearmost leaf, 100 the free edge of the latter leaf will ride into engagement with the latch 6^a and be locked thereby against operation. This device may also be pivoted to the back, whereby it will fall by gravity into the position shown in 105 Fig. 1, whereby the latch will prevent the operation of all the holders.

110 By constructing the pivotal connections between the holders of sheet metal all heavy parts are avoided, thus materially lessening the weight of the holders, and on account of the long pivotal bearings which I provide, it is possible to connect the holders together with one set of connections centrally arranged between the ends thereof 115 instead of two sets of connections arranged near their opposite ends. Also, since each supporting device is bent on longitudinal lines, it will be seen that the bearing plates carried thereby will be readily supported 120 relative to each other and effectively resist all strains endwise of the said devices. It will also be seen that as the bearing members are formed by bending a section of metal at right angles to the bottom wall of 125 130

the supporting device, they will be strengthened in a longitudinal direction and prevented from being bent or twisted on transverse lines, the effect of which being that 5 one bearing plate will serve as a brace for adjoining bearing plates.

To those skilled in the art of making filing appliances of the class described, many alterations in construction and widely differing 10 embodiments and applications of my invention will suggest themselves, without departing from the spirit and scope thereof. My disclosures and the description herein are purely illustrative, and are not intended 15 to be in any sense limiting.

What I claim is:

1. The combination of a series of holders each having a hinge bar, and connections for pivotally connecting the hinge bars together, 20 each connection comprising a supporting device having bottom and side walls arranged to fit snugly the walls of the adjacent hinge bar, a plate interposed between the bottom wall of the supporting device and the adjacent hinge bar and provided with integral bearing members depending from its opposite ends, the said bearing members being formed with openings to receive a pintle, and means for securing the said supporting 25 device to the adjacent hinge bar.

2. The combination of a series of holders, each having a hinge bar, and connections for pivotally connecting the hinge bars together, each connection comprising a supporting device, having bottom and side walls arranged to fit snugly the walls of the adjacent hinge bar, a plate interposed between the bottom wall of the supporting device and the adjacent hinge bar and provided with integral bearing members depending from its opposite ends, the said bearing members being arranged to engage the opposite end edges of the supporting device to prevent movement 35 in a longitudinal direction and formed with 40

openings to receive a pintle, and means for 45 securing the said supporting device to the hinge bar.

3. The combination of a series of holders, and connections for pivotally connecting the holders together, each connection comprising 50 a supporting device adapted to be fixed to an adjacent holder and having a bottom wall, a plate interposed between the bottom wall of the supporting device and the adjacent holder and provided with integral bearing members depending from its opposite 55 ends, the said bearing members being arranged to engage the opposite end edges of the supporting device to prevent movement in a longitudinal direction and formed with 60 openings to receive a pintle, and means for securing the said supporting device to the holder.

4. The combination of a series of holders, each having a hinge bar, connections including pintles for pivotally connecting the hinge bars together, each connection comprising a supporting device having bottom and side walls arranged to fit around the walls of the adjacent hinge bar, a plate interposed between the bottom wall of the supporting device and the adjacent hinge bar and bearing members formed with openings 65 to receive the pintles, depending from its opposite ends, the said plate being of a 70 width to fit between the side walls of said device and of a length to cause the bearing members to engage the opposite end edges of said device, whereby the said plate is held rigidly in position against the adjacent 75 hinge bar, and means for securing each supporting device to an adjacent hinge bar.

In testimony whereof I affix my signature in the presence of two witnesses.

HARRY J. HICK.
